Notice of Allowance dated Jun. 18, 2015 from U.S. Appl No. 29/470,544, 7 pages.

Primary Examiner — Paula Greene

(74) *Attorney, Agent, or Firm* — Knobbe, Martens, Olson & Bear, LLP

(57) **CLAIM**

The ornamental design for a storage device, as shown and described.

DESCRIPTION

FIG. 1 is a top, front and side perspective view of an embodiment of the storage device embodying the new design.

FIG. 2 is a front view thereof.

FIG. 3 is a back view thereof.

FIG. 4 is a first side view thereof.

FIG. 5 is a second side view thereof.

FIG. 6 is a top view thereof; and,

FIG. 7 is a bottom view thereof.

Broken lines are used to illustrate features of the storage device which form no part of the claimed design.

1 Claim, 7 Drawing Sheets
